UNITED STATES PATENT OFFICE.

GEORGE R. RICH, OF CHICAGO, ILLINOIS, ASSIGNOR TO THE GEORGE R. RICH MANUFACTURING COMPANY, OF CHICAGO, ILLINOIS, A CORPORATION OF ILLINOIS.

BORING-TOOL.

SPECIFICATION forming part of Letters Patent No. 728,013, dated May 12, 1903.

Application filed May 31, 1902, Serial No. 109,607. (No model.)

To all whom it may concern:

Be it known that I, GEORGE R. RICH, a citizen of the United States of America, residing at Chicago, in the county of Cook and State of

5 Illinois, have invented certain new and useful Improvements in Boring-Tools, of which the following is a specification.

My invention relates to certain new and useful improvements in boring-tools for use on 10 machine-lathes or other similar machinery; and its object is to provide a device of this class which shall be simple and cheap and which shall be more effective than the devices heretofore in use. It has been customary in 15 the past to use an L-shaped tool, and owing to the obvious mechanical disadvantages of such a structure any attempt to cut a large shaving resulted in breaking it or, at least, in bending it out of shape. For this reason 20 it has been necessary to take off a small shaving at each operation, and this necessitated several repetitions of the boring process before any considerable amount of material could be removed.

25 The object of my invention is primarily to produce a tool which shall have no tendency to break whatever the size of the shaving is and which shall be capable of taking so large a shaving that under ordinary circumstances 30 only one operation will be necessary.

To these and certain minor ends my invention consists in certain novel features of construction, shown in the accompanying drawings, and fully described in the specification.

35 In the drawings, Figure 1 is an elevation of a machine-lathe of the ordinary type with my improved boring-tool thereon. Fig. 2 is a section in the line 2-2 of Fig. 1, showing the construction of the boring-tool and its position relative to the chuck and tail-stock of the lathe and the material operated on. Fig. 3 is a perspective of the cutting bar or tool proper. Fig. 4 is a perspective of the tool-guide and a portion of the tool as it is used 40 when a conical hole is to be cut. Fig. 5 is a perspective of a portion of the tool, showing the means by which the cutting-bar is held in place; and Fig. 6 is a plan, with certain parts in section, of a portion of a lathe and 45 tool when cutting a conical hole.

Referring to Fig. 1, A is a machine-lathe of the ordinary type, having a chuck B, a tail-stock C, and a feed-slide D, all of the ordinary type.

E is the material which it is desired to bore, 55 and, as is customary in such cases, it is finished on the outside and suitably cored on the inside before the boring is begun. A shaft F extends through the cored hole in the material E from the chuck center (designated by f) to the tail-stock center, (designated by c.) This shaft is provided with a longitudinal slot f', the purpose of which will presently be apparent. Upon the shaft F is a sleeve G, substantially of the form shown in Fig. 2, and this sleeve has at the end nearest the tail-stock a brace G', which is shown in Figs. 2 and 4, said brace being secured by a set-screw d to the top of the feed-slide D. The brace is secured to the sleeve G by screws 70 g. The end of the sleeve G nearest to the chuck is pierced by two preferably rectangular holes g' g' in line with each other, these holes being adapted to receive the cutting-tool H. This fits the holes closely and is held 75 in place by two set-screws g².

The tool H is constructed as shown in Fig. 3, and it has two cutting edges h h' at the opposite ends and also upon opposite sides of the tool. One edge h' of the tool is tapered 80 off at h², Fig. 3, so that when in operation the face h' will take off a slightly-thinner shaving than will the cutting-face h.

The tool H is not centrally placed with respect to the sleeve; but the end h' is placed 85 farther from the center than is the end h. This relation is clearly shown in Fig. 2, and it will be evident therefrom that the end h cuts off quite a thick shaving, but of a small radial extent. Then as the material E revolves past the end h it meets the end h', which takes off a shaving somewhat thinner, but of greater radial extent. In other words, one of the ends cuts immediately after the other, and they take off two shavings, which 90 together make a cut of any desired thickness. The cutting-tool H extends through the slot f' in the shaft F, heretofore referred to, and it is fed along by the feed-slide D.

The advantage of this tool over the L- 100

shaped tool heretofore in use lies in the following circumstances: In the first place, the tool is cutting at the same time on opposite sides of the center, and for that reason there is no strain upon the supporting-shaft, so that there is no tendency to breakage.

The second advantage of this tool lies in the fact that one end of the tool takes off approximately half of the shaving and the other end takes off the remainder thereof. The result of this is that a great deal larger shaving can be taken off than with any form of cutter in common use. I have succeeded with this tool in making a cut seven-eighths 15 of an inch broad upon an ordinary lathe. This of course is as large a hole as it is usually desired to make, and so instead of having to run the tool several times through the hole to bring it to the proper size I accomplish the same result with one operation.

When it is desired to cut a beveled hole, as shown in Fig. 6, the tail-stock is moved to one side or the other, and a sleeve G^2 is slipped over the guide G' and is clamped in the feed- 25 slide. This permits a slight angular movement between the feed-slide and the tool-holder.

I realize that considerable changes can be made in the details of this construction without materially departing from the spirit of 30 the invention, and I do not, therefore, desire to limit myself to the specific form shown herein.

I claim as new and desire to secure by Letters Patent—

In a device of the class described, the combination with a chuck and a tool-holder, of a tool supported thereby and extending unequally on opposite sides thereof, the end of said tool which is nearest said tool-holder being advanced beyond the opposite end, whereby said tool is enabled simultaneously to remove a shaving with each of its ends, said shavings being of equal thickness, substantially as described.

In witness whereof I have hereunto set my hand, at Chicago, in the county of Cook and State of Illinois, this 26th day of May, A. D. 1902.

GEORGE R. RICH.
